Primary Examiner — Angela J Lee

(57) **CLAIM**

The ornamental design for a USB memory device, as shown and described.

DESCRIPTION

FIG. 1 is a right side view of the USB memory device with the cap and the shell in a closed position, the left side being the mirror image thereof.

FIG. 2 is a right side view of the USB memory device with the shell in a closed position and the cap in an open position, the left side being the mirror image thereof.

FIG. 3 is a rear view of the USB memory device.

FIG. 4 is a front view of the USB memory device.

FIG. 5 is a top view of the USB memory device with the cap and the shell in a closed position, the bottom view being a mirror image thereof.

FIG. 6 is a top view of the USB memory device with the cap in an open position and the shell in a closed position, the bottom view being a mirror image thereof.

FIG. 7 is a front, top, right side perspective of the USB memory device with the cap and the shell in a closed position.

FIG. 8 is a front, top, right side perspective of the USB memory device with the cap and the shell in an open position.

FIG. 9 is a rear, top, right side perspective of the USB memory device with the cap and the shell in an open position.

FIG. 10 is a cross-sectional view of the cap of the USB memory device, taken along line 10 in FIG. 6.

FIG. 11 is a view of the inside face of the cap of the USB memory device; and,

FIG. 12 is a cross-sectional view of the cap of the USB memory device, taken along line 12 in FIG. 9.

The broken lines shown in the drawings represent portions of the USB memory device that form no part of the claimed design.

1 Claim, 6 Drawing Sheets
